UNITED STATES PATENT OFFICE.

NILS E. NORSTROM, OF CHICAGO, ILLINOIS.

HAIR CLIPPER.

Application filed December 19, 1924. Serial No. 757,057.

My invention relates to hair clippers, and has for its object improvements in devices of that kind. More particularly, my invention relates to the clipping blades, their construction, the connection for driving the movable blade, and an adjustment for one of the blades for purposes which will be hereinafter set forth.

In the accompanying drawings

Fig. 1 is an elevation, partly in section, of a clipper intended to be operated by a magnet enclosed within the case;

Fig. 2 is an enlarged section of both blades, the same being on line 2—2 of Fig.

15 6;

Fig. 3 is a similar section of the blades, but in different relationship to each other;

Figs. 4 and 5 are partial plans of the blades when they are are in the relationship 20 to each other shown in Fig. 3;

Fig. 6 is a plan of the upper blade with its connecting spring;

Fig. 7 is a bottom view of the lower blade;

Fig. 8 is a partial view in the direction 25 of Fig. 1;

Fig. 9 is an enlarged section (corresponding to Fig. 2) of one size of blades now in use; and

Fig. 10 is a similar section of another size 30 of blades now in use.

As a preliminary, I will say that there are now on the market four sizes of blades known, respectively, as "No. 1," "No. 0," "No. 00" and "No. 000." The size "No. 35 000" is the one illustrated at enlarged scale in Fig. 9, is very thin, and is for cutting hair very short. Fig. 10 is a similar section of "No. 0," which is thicker, and does not cut hair so close. "No. 00" is an intermediate size, and "No. 1" is thicker than the one shown in Fig. 10. To meet requirements, barbers usually have to keep on hand a surplus of clippers, each with its own size of blade, and dealers have to carry a

40 stock containing all sizes. As will be explained hereinafter, a single pair of blades, such as I show in Fig. 2, is capable of all of the results produced by the four standard sizes now recognized in the trade. Making 45 one size serve all of the purposes of four sizes is an ultimate object of the present invention.

In the said drawings, 11 is a case for containing a motor magnet, the armature of 50 which is shown at 12. The magnet may be like that shown in my pending application,

Serial Number 688,645, filed January 26, 1924, or like any other magnet used in this class of devices.

55 Mounted on a heel 13 on case 11 is a stationary clipper blade 14 held in place by screws 15, and mounted upon the stationary blade is a movable blade 16. On the upper face of blade 16 is a spring 17 held in place by screws 18. This spring has the 60 general shape of an ordinary "Z-bar," but has proportions as shown in Fig. 2. The upper free part of the spring is not parallel to the part secured to the blade, but inclines outward as shown in Fig. 2. This free part 65 is notched at front and rear so as to leave a short bridge 19. The end of the armature lever 12 is notched at 20 to form a fork to receive the bridge 19 and hold the blade 16 from inward or outward movement. The 70 bottom of the notch 20 and the upper face of bridge 19 are not parallel with each other, with the result that the longitudinal thrust of the armature lever 12 comes on the outer edge of the bridge 19. This point 75 of contact on the spring 17 is at approximately the center of the blade 16, and the longitudinal thrust on this point serves to hold blade 16 against blade 14 with a spring tension.

80 Secured on the upper face of the spring 17, at each side of the bridge 19, are stiff spring brackets 21 of the general shape shown in Figs. 1, 6 and 8. The distance between these brackets is such that when the 85 notch 20 in the end of armature lever 12 is made to engage bridge 19, the brackets press with considerable force against opposite sides of the armature lever at points just above the notch 20. When the armature 90 lever is vibrated to drive the movable blade 16, the driving action is from the lever thru these brackets to the blade 16. To facilitate the entry of the end of the armature lever between these brackets, the extreme end of 95 the lever is tapered as shown in Fig. 8.

100 The bottom of the blade 14 has longitudinal grooves cut therein as shown in Fig. 7, and as is common in the stationary blades of clippers. The ribs left by the cutting of 105 these grooves match the teeth of the blades as shown.

110 The stationary blade is held in place by screws 15 which pass thru slots 22 in blade 14. Around these slots are countersinks 23 for the heads of screws 15. As so constructed, the blade 14 is adjustable in or out

under blade 16 to any position between that shown in Fig. 2 to that shown in Fig. 3.

Referring to Figs. 9 and 10, the movable blade 24 of ordinary clippers is the same in 5 different devices, but the lower blade is varied to produce varied results. In Fig. 9, the under surface of blade 25 is made concave so that the thickness of the lower teeth 27 will be of substantially the same for 10 a considerable length of tooth. The purpose is to clip the hair very short. In Fig. 10, the teeth 28 of blade 26 is made thicker with the result that hair cut with the blades shown in Fig. 10 will not be so short as it 15 will be when cut with the blades shown in Fig. 9. As stated before, there are four different kinds of lower blades carried in stock by dealers to meet the varied requirements of the trade.

20 I have discovered that when the movable blade is operated at the speed common in hair clippers of the present character, the actual cutting is done very close to the tip of the teeth of that blade which is further 25 to the rear. As the lower blade is made to project slightly beyond the upper blade to protect the skin, this means that the actual cutting is done at the tips of the teeth of the upper blade.

30 Referring now to Figs. 2 and 3, I make the ribs under the teeth of the lower blade convex as shown at 29. When the blades have the relationship shown in Fig. 2, the 35 length of hair remaining after clipping will be that distance which is between the tip of the tooth 30 and the nearest point on the convex rib 29. The real cut is even shorter than that because, in practice, the convex surface sinks slightly into the skin under 40 pressure. When the lower blade has been advanced to the position shown in Fig. 3, the length of remaining hair will be the distance between tip 30 and the nearest point on the convex surface, less whatever amount 45 that convex surface presses into the skin.

In Fig. 9, the under surface of the teeth of the lower blade is concave, and in Fig. 10 the under surface is shown as straight. Making the under surface concave or 50 straight for all gauges of under blades seems to have been the common practice of all manufacturers up to the present time.

Making the under surface convex, as I 55 show it in Figs. 1, 2 and 3, has several advantages in connection with an adjustment such as I provide. One advantage is that a

very small adjustment of one blade with respect to the other makes considerable variation in the closeness of the clip. Another advantage is that convex ribs sink more 60 readily into the surface being clipped, with the result that it is possible, by adjusting the angle of the clipper to the surface to be clipped, to make a closer clip than is possible with a concave surface such as is 65 shown in Fig. 9.

A third advantage arises from the fact that small differences of pressure will cause a convex surface to sink different distances into the surface being clipped. As a consequence of this last, a barber can vary the closeness of the clip by simply varying the pressure he applies, and without varying the adjustment of the blades. This particular result cannot be obtained to a material extent by a blade with a concave under side 75 because such a form bears against a large area and pushes the whole surface back without bringing the teeth of the upper blade nearer to the surface being clipped. 80

What I claim is:

1. In a device of the class described, a case, a stationary blade, a movable blade mounted on the stationary blade, a spring secured to the back of the movable blade, 85 and a driving lever furnishing a thrust on the back of said spring, said spring and lever having a slipping connection with each other, and said lever acting thru said spring to locate the movable blade with respect to 90 the stationary blade.

2. In a device of the class described, a case for containing a power device, a stationary blade secured to the case, a movable blade mounted upon the stationary 95 blade, a spring secured to the back of the movable blade, a driving lever furnishing a thrusting force on the spring and also embracing a portion of said spring so as to hold the movable blade at a predetermined 100 relationship to the stationary blade, and brackets secured to said spring and serving to embrace the sides of the driving lever.

3. In a device of the class described, a case, a stationary blade secured to the case, 105 a movable blade mounted on the stationary blade, a Z-shaped spring having one flange secured to the movable blade, and a driving lever having a slipping connection with the other flange of said spring.
